DEPOSITING OF SAND UNDER WATER

Aage Einer Bretting, Copenhagen, Denmark, assignor to Christiani & Nielsen, Copenhagen, Denmark, a registered Danish firm

Application December 1, 1937, Serial No. 177,636
In the Netherlands December 7, 1936

12 Claims. (Cl. 61—63)

The present invention relates to a method of depositing sand under water and to a device for carrying out the method.

For the sake of simplicity it has been referred here and in the following specification and claims to sand only. The invention, however, is as well applicable to the use of other cohesionless materials such as pebble and small or larger stones or crushed stone.

10 The difficulties that have hitherto been experienced in connection with the depositing of sand under water consist mainly in the impossibility of depositing the sand to a definite extent and in a predetermined form.

15 The object of the present invention is to obviate these difficulties, and it consists therein that a quantity of sand and water is forced through a pressure pipe with simultaneous suction through one or several other pipes. The orifice of the suction pipe or of each suction pipe is so disposed in relation to the orifice of the pressure pipe that the suction flow together with the flow from the pressure pipe determines the path of the sand grains issuing from the pressure 20 pipe.

25 The accompanying drawings illustrate the method according to the invention, and a device for carrying out the method.

Figure 1 is a diagrammatic view illustrating a 30 subaqueous deposit of sand in the course of being deposited and illustrating schematically a portion of the apparatus used.

Figure 2 is a vertical sectional view taken on the section line II—II of Figure 1.

35 Figure 3 is a vertical sectional view taken on the section line III—III of Figure 1.

Figure 4 is a vertical sectional view taken on the section line IV—IV of Figure 1.

Figure 5 is an elevational view illustrating the 40 apparatus used when sand is to be introduced between a dredged river bed and a tunnel element placed in the river.

Figure 6 is a diagrammatic plan view of the device shown in Figure 5 on a smaller scale.

45 Figure 7 is a cross sectional view taken through the nozzle portion of the pipes along the section line 1—1 of Fig. 1 looking in the direction of the arrows.

Figure 8 is a partial cross sectional view of the 50 orifice of the pipes illustrating the use of guide members with the nozzle and,

Figure 9 is a cross sectional view of a modified nozzle.

With particular reference to Figs. 1—4 the 55 surface of the water is indicated by 1, and 2 indi-

cates the bed on which the sand is to be deposited. Three pipes 3, 4 and 5 arranged adjacent one another, are bent horizontally under water and enter into a common nozzle 6. A mixture of sand and water is forced through the central 5 pipe 4, whereas the pipes 3 and 5 at either side thereof serve as suction pipes. In the common nozzle 6 the orifice of the pressure pipe 4 projects somewhat beyond the orifices of the two suction pipes 3 and 5.

10 Through the pressure pipe 4 a mixture of sand and water is forced, and at the same time suction is produced in the pipes 3 and 5. At the beginning the nozzle 6 remains stationary. The sand contained in the jet forced through the 15 pressure pipe settles, while water only issues from the suction pipes 3 and 5. After a while sand will appear in water flowing through the suction pipes. The sand concentration in the flow through the suction pipes will gradually increase 20 and before long this sand concentration will be equal to the sand contents in the mixture forced through the pressure pipe, and from now on no further deposit of sand takes place. The nozzle 6 with the pipes 3, 4 and 5 is thereupon drawn a 25 short distance back in the direction indicated by the arrow 7 in Fig. 1, and the above described process is thereupon repeated.

30 Experiments have proved that in this manner the entire space between the bed 2 and the surface 1 of the water may be filled with a uniform and compact deposit of sand. The width of the deposit is dependent on the diameter of the pipes and the velocity in the pipes. On both sides and in front of the nozzle 6 the sand is deposited with 35 the natural slope, which in Figs. 2 and 3 is indicated by the angle 8.

The illustrations in Figs. 1—4 show to scale the results that have been obtained by means of an apparatus built for experimental purposes.

40 Figs. 5 and 6 illustrate a device by means of which sand may be introduced between a dredged river bed 9 and a tunnel element 10 submerged in the river. The highest level of the river water is indicated by 11.

45 The device comprises a bridge 12 travelling lengthwise on rails 13, placed on the roof of the submerged tunnel element. This bridge carries spouting towers 14, which are arranged on the bridge 12, movable at right angle to the direction 50 in which the latter is movable.

A vertical pipe system 15, which as a unit can 55 revolve about its vertical axis, and which comprises a pressure pipe 16 along either side of which there is placed a suction pipe 17 is sus-

bended in each of the spouting towers 14. The lower part of these three pipes are all horizontally bent so as to extend into the slotted space 18 between the base of the tunnel element and 5 the river bed.

Fig. 7 is a sectional view of the horizontal part of the pipes. On both sides of the suction pipes 17 air chambers 19 are placed providing the long, freely cantilevered pipe ends with sufficient buoyancy to enable them to maintain their horizontal position.

Furthermore the horizontal part of the pipes may be provided with rollers 20 or similar guide members (Fig. 8), serving to support and guide 15 the pipes along the lower surface of the structure 10.

The tunnel element illustrated in Fig. 5 is placed horizontally above the river bed. Hence, it has been referred above to vertical pipe systems 15 and horizontally bent pipe ends. It will, however, be understood that in case the tunnel element is inclined, as for instance in the case of the ramp portions, the pipe system 15 would no longer be arranged vertically, but at a right 25 angle to the lower surface of the tunnel element. The axes on which the pipe systems rotate will likewise alter their position as will do also the horizontal ends.

The manner in which the sand is deposited in 30 the space 18 is the same as that described in connection with Figs. 1-4.

The time at which the spouting towers 14 should be moved in order to obtain a progressive dense deposit of the sand is determined by means 35 of the concentration of sand in the mixture of water and sand issuing from the suction pipes 17.

It is furthermore possible to give the spouting towers a slow and continuous rearward movement. As long as only water is discharged by the 40 suction pipes, all sand forced through the pressure pipe is deposited. When, however,—in the case of equal quantities of forced in and discharged mixture—the mixture issuing from the suction pipe has the same concentration of sand 45 as the mixture forced through the pressure pipe, no sand will be deposited. If the spouting towers are moved in the first mentioned case the displacement has taken place too early. If, however, they are not displaced until the concentration 50 of sand is alike in the suction and in the pressure pipes as mentioned in second case, there has been an unnecessary delay.

In practice the initial moving of the tower should take place when the mixture issuing from 55 the suction pipes has reached a certain concentration of sand—a concentration that should be maintained by moving the towers simultaneously.

The concentration of sand may be checked 60 from the top of the spouting towers far from the inaccessible place where a deposit of sand is required. It is advisable to measure the concentration of sand in the mixtures flowing through the suction and pressure pipes in smaller branch 65 pipes, thus operating with smaller quantities, which facilitates the measuring.

Finally it is to be remarked that also a pressure pipe 16 and a suction pipe 17 may be arranged within a common nozzle in such a manner 70 that the suction pipe is arranged concentrically around the pressure pipe (Fig. 9). Other arrangements of the orifices of the suction and pressure pipes in relation to each other are possible, either within a common nozzle or separately.

By the above invention it is possible to control the otherwise uncontrollable movements of the sand grains, as well as to control the extent and density of the sand deposit.

Thus a sand fill of a geometrically defined 5 shape can be made, and this has been proved by experiments.

According to the invention the pressure flow and the suction flow are preferably directed parallel or approximately parallel to the bed on to 10 which the sand is to be deposited.

Furthermore the depositing of the sand may according to the invention at will be performed intermittently or continuously at a comparatively low speed by displacing the orifices of the pipes 15 in accordance with the rate at which the sand is being deposited.

The correct time for moving the orifices of the pipes, or the speed at which they are moved, is according to the invention determined on the 20 basis of the relation between the contents of sand in the mixture flowing through the suction pipes and the contents of sand in the mixture that is forced through the pressure pipe.

In practice the method according to the invention will usually be carried out in such a manner that at the start sand will be deposited through stationary pipes, while water only will flow through the suction pipe or pipes. Gradually, however, only a portion of the sand issuing 30 from the pressure pipe will be deposited, while a quantity thereof will return through the suction pipes.

When the concentration of sand in the stream 35 in the suction pipe or pipes finally becomes equal to that in the pressure pipe, this proves that no more sand is being deposited. The pressure pipe and the suction pipe or pipes are then moved backwards, whereupon a renewed deposit of sand takes place, and the concentration of sand in the 40 stream through the suction pipe or pipes is at the same time correspondingly reduced.

Through experiments made it has been proved that the sand is being deposited with a gradient equal to the natural slope of the material, and 45 the width of the deposit is dependent on the velocity in the pipe.

According to the invention there may be employed a nozzle common for the pressure pipe and the suction pipe or pipes, which encloses the orifices of these pipes. The diameter of the pipes have a bearing on the width of the sand fill produced.

The dimensions of the deposit of sand is thus a definite function of the velocity in the pipe 55 and of the diameters of the pipes. It is consequently possible to obtain a dense filling of sand also in narrow spaces in which the depositing cannot be observed from the exterior.

This fact may be utilized with advantage in 60 the depositing of sand beneath a foundation, a tunnel element or any other submerged structure the underside of which is located at a certain distance above the water bottom.

The device by means of which the method may 65 be carried out comprises according to the invention a bridge traveling on or above the upper side of the submerged structure in question. Upon this bridge one or several movable spouting towers are placed. Within each of these towers a pipe system including a pressure pipe and one or several suction pipes are suspended in 70 such a manner that the pipe system as a unity can revolve about a vertical axis. This pipe system extends downwards below the bottom of the 75

structure, where it is bent so that the orifices of the pipes may be horizontally introduced into the space between the said water bottom and the bed.

Finally measures may be taken to provide the 5 horizontal part of the pipe system with additional buoyancy or to arrange such guides that will secure the proper position of this part of the pipe system in relation to the bottom of the structure also in case this part is of exceptional 10 length.

When sand is to be deposited under water with a free surface and where the water level is not too high in relation to the mouth of the tubes, the sand may be deposited as high as the water 15 level, but it will not rise above it.

In the following claims the term "sand" covers any cohesionless material.

I claim:

1. A method of depositing sand under water 20 which comprises subjecting a mixture of sand and water to pressure so as to direct said mixture in a direction approximately parallel to the bed on which said sand is to be deposited and at the same time establishing a suction flow in a direction 25 approximately parallel to said bed.

2. A method of depositing sand under water comprising forcing a mixture of sand and water through an orifice subjected at the same time to the influence of a suction flow closely adjacent 30 said orifice and then displacing said orifice in accordance with the rate at which sand is deposited.

3. A method of depositing sand under water comprising forcing a mixture of sand and water 35 through an orifice under pressure, subjecting said mixture of sand and water to the influence of a suction flow closely adjacent said orifice and then displacing said orifice in accordance with the relation existing between the contents of sand in 40 the mixture of sand and water and the contents of sand in said suction flow.

4. A device for depositing sand under water comprising a number of open ended pipes, the ends of which are positioned under water and 45 substantially parallel to a bed on which the sand is to be deposited; means for forcing a mixture of sand and water through one of said pipes and means for exerting a suction in another of said pipes; means for displacing the pipes continuously 50 backward at a slow speed according to the rate at which the sand issuing from the pipe through which the mixture is being forced is deposited upon said bed.

5. A device for depositing sand under water 55 comprising a number of open ended pipes, the ends of which are positioned under water and substantially parallel to a bed on which the sand is to be deposited; means for forcing a mixture of sand and water through one of said pipes and 60 means for exerting a suction in another of said pipes, means for displacing the pipes intermittently backward along small distances according to the rate at which the sand issuing from the pipe through which the mixture is being forced is 65 deposited upon said bed.

6. A device for depositing sand under water, comprising a number of open ended pipes the ends of which are positioned under water and substantially parallel to a bed on which the sand 70 is to be deposited, means for forcing a mixture of sand and water through one of said pipes and means for exerting a suction in another of said pipes, means for displacing the pipes backward at such a speed as may be determined by the 75 relation between the contents of sand in the mix-

ture issuing from the suction pipe and the contents of sand in the mixture forced through the pressure pipe.

7. A device for depositing sand under water 5 comprising a number of pipes, the orifices of which are located beneath the water level; means for forcing a mixture of sand and water through one of said pipes and means for exerting a suction on another of said pipes, the orifice of the suction pipe being so disposed in relation to the orifice of the pressure pipe that the flow in the water caused by the suction in the suction pipe together with the flow in the water caused by the pressure action in the pressure pipe determines the path of motion of the sand grains issuing 10 from this latter pipe, the ends of the pipe near the orifices thereof being positioned in such a way with respect to the bed on which the sand is to be deposited that both the pressure flow and the suction flow are directed substantially parallel to said bed.

8. A device for depositing sand under water 20 comprising a number of pipes having their orifices located beneath the water level, means for forcing a mixture of sand and water under pressure through one of said pipes, means for exerting a suction on another of said pipes, so that the flow in the water caused by the suction in the suction pipe together with the flow in the water caused by the pressure action in the pressure pipe 25 determines the path of motion of the sand from said pressure pipe, and a common nozzle enclosing the ends of said pipes.

9. A device for depositing sand under water 30 comprising a number of pipes having their orifices located beneath the water level, means for forcing a mixture of sand and water under pressure through one of said pipes, means for exerting a suction on another of said pipes, so that the flow in the water caused by the suction in 40 the suction pipe together with the flow in the water caused by the pressure action in the pressure pipe determines the path of motion of the sand from said pressure pipe and the ends of the pipes under water being arranged in a common 45 nozzle comprising the orifice of a centrally located pressure pipe and the orifices of two suction pipes being located on either side of said pressure pipe.

10. A device for depositing sand under water 50 comprising a number of pipes having their orifices located beneath the water level, means for forcing a mixture of sand and water under pressure through one of said pipes, means for exerting a suction on another of said pipes, so that 55 the flow in the water caused by the suction in the suction pipe together with the flow in the water caused by the pressure action in the pressure pipe determines the path of motion of the sand from said pressure pipe, a traveling bridge, 60 a spouting tower on said bridge, means for revolving said pipes about a substantially vertical axis, means for suspending said pipes from said tower and the lower ends of said pipes being bent.

11. A device for depositing sand under water 65 comprising a number of pipes having their orifices located beneath the water level, means for forcing a mixture of sand and water under pressure through one of said pipes, means for exerting a suction on another of said pipes, so that 70 the flow in the water caused by the suction in the suction pipe together with the flow in the water caused by the pressure action in the pressure pipe determines the path of motion of the sand from said pressure pipe, a traveling bridge, 75

a spouting tower on said bridge, means for revolving said pipes about a substantially vertical axis, means for suspending said pipes from said tower and the lower ends of said pipes being bent, and air boxes provided upon the bent portions of said pipes.

12. A device for depositing sand under water comprising a number of pipes having their orifices located beneath the water level, means for forcing a mixture of sand and water under pressure through one of said pipes, means for exerting a suction on another of said pipes, so that

the flow in the water caused by the suction in the suction pipe together with the flow in the water caused by the pressure action in the pressure pipe determines the path of motion of the sand from said pressure pipe, a traveling bridge, a spouting tower on said bridge, means for revolving said pipes about a substantially vertical axis, means for suspending said pipes from said tower and the lower ends of said pipes being bent, and guiding members provided upon the bent portions of said pipes.

AAGE EINER BRETTING.
